UNITED STATES PATENT OFFICE.

GEORGE E. ADAMS, OF NEW BRITAIN, CONNECTICUT.

DESIGN FOR A BUCKLE.

SPECIFICATION forming part of Design No. 22,337, dated April 11, 1893.

Application filed March 16, 1893. Serial No. 466,355. Term of patent 7 years.

To all whom it may concern.

Be it known that I, GEORGE E. ADAMS, of New Britain, in the county of Hartford and State of Connecticut, have invented and produced a new and original Design for Buckles Adapted for Personal Wear, of which the following is a specification, reference being had to the accompanying drawing, and to the letters of reference marked thereon.

Said drawing represents in front elevation a buckle embodying my present design and applied to a suspender web.

The essential feature of the design will be seen from the drawing to consist in the ornamental conventionalized configuration of a butterfly or like insect, given to the portion of the buckle overlying the web.

In the illustration, the conventionalized insect configuration is shown attached by the

representations of the antennæ C of the insect, and by the upper edges of the anterior or first portion of the wings D to the lower side of a bar A. The body B of the insect is narrowed to indicate the head, thorax and abdomen and has middle and posterior wing sections E attached thereto. The interior portions of the wings are of open or fret work, while the scalloped edges are shown of considerable thickness and have ornamental configurations thereon for artistic effect.

What I claim, and desire to secure by Letters Patent, is—

The design for a buckle herein shown and described.

GEORGE E. ADAMS.
